Primary Examiner — Cynthia Ramirez(74) *Attorney, Agent, or Firm* — Hankin Patent Law, APC; Kevin Schraven; Jimmy Sauz(57) **CLAIM**

The ornamental design for hand hydraulic floor jack, as shown and described.

DESCRIPTION

FIG. 1 is a top perspective view of the hand hydraulic floor jack, showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines are for the purpose of illustrating environmental structure and unclaimed subject matter and form no part of the claimed design.

1 Claim, 6 Drawing Sheets(56)
